U.S. Appl. No. 29/362,030, filed May 19, 2010, Wilson et al.

Primary Examiner — Mark Goodwin

(74) *Attorney, Agent, or Firm* — Oblon, Spivak, McClelland, Maier & Neustadt, L.L.P.

(57) **CLAIM**

The ornamental design for a tray and lid assembly, as shown and described.

DESCRIPTION

FIG. 1 is a top, front, and right side perspective view of a tray and lid assembly;

FIG. 2 is a front elevational view thereof;

FIG. 3 is a left side elevational view thereof, the right side elevational view being a mirror image of the left side elevational view shown;

FIG. 4 is a top plan view thereof;

FIG. 5 is a bottom plan view of the tray;

FIG. 6 is a bottom and front perspective view of the tray;

FIG. 7 is a front elevational view of the tray;

FIG. 8 is a left side elevational view of the tray;

FIG. 9 is a top plan view of the tray;

FIG. 10 is an exploded view of FIG. 1; and,

FIG. 11 is a front and right side perspective view thereof, shown in use with bottles disposed within the assembly. The broken lines in the drawings depict environmental subject matter only and form no part of the claimed design.
